UNITED STATES PATENT OFFICE.

NELSON W. MORLEY, OF MENTOR, OHIO, ASSIGNOR TO DODGE COAL STORAGE COMPANY, OF NAUGATUCK, CONNECTICUT, A CORPORATION OF CONNECTICUT.

HOISTING APPARATUS.

No. 923,685.

Specification of Letters Patent.

Patented June 1, 1909.

Application filed February 15, 1908. Serial No. 416,015.

To all whom it may concern:

Be it known that I, NELSON W. MORLEY, a citizen of the United States, residing in Mentor, Ohio, have invented certain Improvements in Hoisting Apparatus, of which the following is a specification.

My invention relates to that class of hoisting apparatus known as "telphers", on which a carriage is mounted upon overhead tracks, the carriage carrying the motive power, the bucket and the means for operating the bucket.

The object of my present invention is to so design apparatus of this type that the bucket can be turned at any elevation so that it can be used in unloading vessels which have narrow hatchways, in which the bucket should be turned so as to avoid, as much as possible, shoveling by hand.

Referring to the accompanying drawings:—Figure 1, is a side view of sufficient of a telpher to illustrate my invention; Fig. 2, is a plan view of Fig. 1; Fig. 3, is a transverse sectional view on the line 3—3, Fig. 2; Fig. 4, is a detached side view of one of the carriers; Fig. 5, is a plan view of one of the carriers; and Fig. 6, is a plan view of a portion of Fig. 2, showing the trucks in a different position.

A, A are the overhead rails supported by any suitable structure; these rails may be of any length desired according to the distance the telpher has to travel. Telphers are used extensively for conveying material from a wharf or railway to a factory building or from a mine to a point where the material is to be used or shipped. Usually the length of the line is comparatively short.

B is the telpher having wheels b mounted upon rails A. There are four sets of wheels in the present instance, although the number of wheels will depend considerably upon the length and the weight of the telpher carriage. The carriage has a depending portion B' hanging a sufficient distance below the rails A to contain the operating cab B² and the hoisting drums C, C'. The telpher is driven by the motors b', there being two in the present instance geared to two of the axles of the wheels b.

C² is the motor, which drives the hoisting drums C, C'.

D is the bucket which may be of any type, in the present instance this bucket is of the clam shell type; the buckets proper d, d be-

ing operated to move apart and to be elevated in respect to the body portion so that the bucket can be lowered directly onto the coal or other material and drawn together, picking up sufficient coal to form a load. 60 The bucket in the present instance is suspended from two sets of ropes c, c', one set of ropes passing around suitable sheaves on the bucket and on the carriers E and F respectively to the drums C and C'. 65

Each carrier is made as shown in Figs. 4 and 5, and I will now describe the carrier E. This carrier consists of a beam E' having at one end bearings E² for the axle of the sheaves e, e' and having at the other end a bearing E³ for the axle of the sheaves e², e³ and at the forward end of the carrier is a vertical pin i which extends through a truck I having wheels i' and at the rear end of the carrier is a pin i² passing through a truck I' 75 having wheels i³. Thus the carrier is suspended from these two trucks and the rear truck is adapted to rails G, G extending parallel with the side members of the telpher carriage, while the forward truck is adapted 70 to rails H, H set at an angle as clearly shown in Fig. 2. The purpose of this will be described hereafter.

Connected to the rear pin i² is a head K to which is adapted a rod k from a piston 85 mounted in a hydraulic cylinder K' and also attached to this head is a rod k' leading to a controlling cylinder K² which acts as a dash pot so as to prevent the carrier E moving beyond a predetermined point.

The carrier F is similar in every respect to the carrier E except that the beam F' is shorter than the beam E', and the trucks I² and I³ of the carrier F are adapted to rails in a manner similar to the carrier E; the wheels of the truck I³ being adapted to rails parallel with the rails G, while the wheels of the truck I² are adapted to rails H' set at an angle and parallel with the rails H. 95

It will be noticed that the rails are set at such an angle that when the carriers are in the positions shown in Fig. 1, the truck I² is directly back of the truck I and the ropes lead from the carriers so that the length of the bucket is longitudinally disposed with respect to the length of the telpher. 100

When one carrier is withdrawn and the other moved forward, then they assume the positions as shown in Figs. 3 and 6, turning the bucket a half turn. This turning of 110

the bucket can be accomplished when the bucket is at any height.

The invention is particularly adapted for use in removing loads of either coal, ore, or other granular material from vessels which are provided with long and narrow hatchways, and as the buckets are long and narrow they can be lowered into the hatchway while in one position and in order to reach the material which is not directly under the hatchway the bucket can be turned at right angles to the length of the hatch, thus extending under the deck at each side of the hatchway and when lowered onto the material in the vessel it will remove the material which is inaccessible to the ordinary clam shell bucket which is not turned after entering the hatchway. When the bucket is closed with the load it is again turned and raised out of the hold of the vessel and can then be carried to the point of discharge. It will be understood, however, that my invention can be used for purposes other than unloading of vessels, where it is desired to turn the bucket.

I claim:—

1. The combination in a hoisting apparatus, of two tracks set at an angle to the longitudinal line of the apparatus, carriers adapted to the tracks, a rope extending from each carrier and from which the load is suspended, and means for shifting one carrier in one direction and the other carrier in the opposite direction so as to turn the load.
2. The combination in a hoisting apparatus, of a frame, two tracks set at an angle to the longitudinal line of the apparatus, a carrier having trucks adapted to the tracks, rope sheaves on each carrier, ropes extending around the rope sheaves, a hoisting bucket adapted to the ropes, said ropes extending to the hoisting mechanism, and means for moving one carrier forward and the other carrier backward so as to turn the bucket.
3. The combination of a frame, two sets of tracks mounted on the frame, the forward tracks of each set being arranged at an angle, two carriers each having trucks at each end mounted on the tracks, sheaves on the carriers, hoisting ropes passing around the sheaves and adapted to a bucket, and means for moving one carrier forward and the other backward so as to shift the position of the forward trucks on their tracks to turn the bucket.
4. The combination in a telpher, of a carriage, overhead tracks supporting the carriage, two sets of rails mounted on the carriage, the rear rails of each set being arranged longitudinally in respect to the carriage, the forward rails of each set being arranged at an angle in respect to the carriage, two carriers having trucks at each end, the trucks of one carrier being arranged to be carried by one

set of rails and the trucks of the other carrier being mounted on the other set of rails, sheaves on each carrier, hoisting mechanism and a bucket, ropes passing from the hoisting mechanism over the sheaves to the bucket, and means for moving one carriage forward and withdrawing the other carriage, causing the trucks to travel on the angularly set rails and to turn the bucket.

5. The combination in a telpher, of an overhead track, a carriage arranged to travel on said track, hoisting mechanism mounted on the carriage, two sets of tracks on the carriage, the forward set being arranged at an angle to the longitudinal line of the carriage, the rear tracks of each set extending parallel with the longitudinal line of the carriage, two carriers having trucks mounted on said tracks, rope sheaves on each end of each carrier, ropes passing from the hoisting mechanism around the sheaves, a clam shell hoisting bucket carried and operated by the ropes, means for moving the carriers longitudinally, said means being operated so that one carrier will be moved backward while the other carrier is moved forward, causing the trucks to move in opposite directions on the angular tracks and to turn the bucket.

6. The combination of a telpher, of an overhead track, a carriage, hoisting mechanism mounted on the carriage, two sets of tracks on the carriage, the rear set of tracks being parallel with the longitudinal line of the carriage, the forward tracks being set at an angle to the longitudinal line of the carriage, two carriers, trucks pivoted to each end of each carrier, said trucks being adapted to the above mentioned rails, sheaves on each end of each carrier, a hoisting bucket, ropes extending from the hoisting mechanism around the sheaves and connected to each side of the hoisting bucket, with means for moving each carrier longitudinally, one carrier being moved in a reverse direction to the other carrier so as to turn the bucket.

7. The combination of overhead tracks, a carriage suspended from the tracks, a motor on the carriage, two sets of tracks arranged side by side on the carriage, the rear tracks of each being parallel with the longitudinal line of the carriage, the forward tracks being arranged at an angle to the carriage and parallel with each other, two carriers each having swivel trucks at each end adapted to the tracks, the trucks of each carrier being adapted to one set of rails and the trucks of the other carrier being adapted to the other set of rails, sheaves on each end of each carrier, ropes extending from the hoisting mechanism around the sheaves to the buckets, two air cylinders and pistons, one piston connected with one carrier and the other piston connected with the other carrier, and means for controlling the flow of air to the cylinders to operate the carriers.

8. The combination of overhead rails, a carriage suspended from the rails, hoisting mechanism mounted on the carriage, two sets of rails on the carriage, the forward set of rails being arranged at an incline with the longitudinal line of the carriage, two sets of carriers, trucks mounted on the carriers, said carriers being arranged side by side, one truck of each carrier being arranged to travel on the forward rails and the rear truck of each carrier being mounted on the rear set of rails, each carrier being made up of a beam and two bearings at each end, the trucks being swiveled to the bearings, sheaves in the bearings, ropes passing from the hoisting mechanism over the sheaves and a bucket to which the ropes are adapted, said ropes supporting and actuating the bucket, and means for moving the carriers longitudinally, one carrier being moved forward while the other carrier is moved backward so as to cause the bucket to turn as the forward trucks travel on the inclined rails.

9. The combination of operating means consisting of two cylinders and a piston and piston rods therein, two sets of rails, the rear rail of each set being arranged parallel with the line of the cylinders, the forward set being arranged at an incline with respect to the line of the cylinders, two carriers mounted side by side, one supported by the forward and rear trucks of one set and the other supported by the forward and rear trucks of the other set, one piston rod connected to one carrier and the other piston rod connected to the other carrier, a bucket hung from said carriers, the whole being so arranged that when the carriers are moved in opposite directions the bucket will be turned.

10. The combination of a carriage, hoist-

ing mechanism on the carriage, two sets of rails arranged on the carriage, the forward set of rails being inclined with respect to the longitudinal line of the carriage, the other set of rails being arranged parallel to the longitudinal line of the carriage, two carriers arranged side by side, each carrier consisting of a beam and a bearing at each end, sheaves mounted in each bearing, trucks pivoted to the bearings and adapted to the rails, two cylinders, pistons projecting from the cylinders, one piston being pivoted to the rear end of one carrier and the other piston being pivoted to the rear end of the other carrier, ropes passing from the hoisting mechanism around the sheaves, and a bucket attached to the ropes.

11. The combination of overhead tracks, a telpher carriage mounted on the tracks, hoisting mechanism supported by the carriage, two sets of rails, the forward set of rails being arranged at an angle with respect to the longitudinal line of each carriage, the rear rails being arranged parallel to the line of the carriage, two carriers having trucks at each end adapted to the rails of the carriage, two sheaves at each end of each carrier, hoisting ropes passing from the hoisting mechanism around the sheaves of the carriers, and a clam shell bucket hung from said ropes and actuated by the hoisting mechanism, with means for moving the carriers longitudinally so as to shift the position of the ropes and to turn the bucket.

In testimony whereof, I have signed my name to this specification, in the presence of two subscribing witnesses.

NELSON W. MORLEY.
